UNITED STATES PATENT OFFICE.

GEORGE B. BEALE AND DAVID SASSEMAN, OF CHICAGO, AND FRED H. SMITH, OF OAKPARK, ILLINOIS.

MACHINE FOR CUTTING METAL.

SPECIFICATION forming part of Letters Patent No. 684,667, dated October 15, 1901.

Application filed November 17, 1900. Serial No. 36,849. (No model.)

To all whom it may concern:

Be it known that we, GEORGE B. BEALE and DAVID SASSEMAN, residing at Chicago, and FRED H. SMITH, residing at Oakpark, in the county of Cook and State of Illinois, citizens of the United States, have invented certain new and useful Improvements in Machines for Cutting Metal, of which the following is a specification.

10 In the art of milling, turning, boring, and similarly working metal it is customary to "lubricate" the cutter. This is done in various ways, depending upon the construction of the machine. Usually it is done by caus-

15 ing a stream of oil or other lubricant to fall on the cutter and work, so as to keep the cutter at all times flooded. It has also been proposed to make the cutter hollow and provide it with radial passages leading to grooves be-

20 tween the teeth, so that oil discharged into the interior of the cutter will find its way to the grooves and thence to the teeth. In no instance, however, has the oil been delivered to the cutting edge of the cutter in the manner and at the velocity hereinafter described.

25 GEORGE B. BEALE, one of the present applicants, has discovered that the speed of any given machine may be greatly increased by increasing the velocity of the lubricant dis-

30 charged on the teeth of the cutter; and the object of the present invention is to provide a machine by which this can be accomplished.

To this end the present invention consists in the features of novelty that are hereinaf-
35 ter described, and in order that it may be fully understood we will describe it with reference to the accompanying drawings, which are made part hereof, and in which—

Figure 1 is a side elevation of a milling-machine embodying the invention. Fig. 2 is an enlarged horizontal section of a portion thereof on the line 2 2, Fig. 1, looking downward. Fig. 3 is an enlarged vertical section of the upper portion thereof, the section being taken 45 in the axial plane of the mandrel. Fig. 4 is an enlarged vertical section of the lower portion thereof, the section being taken in the axial plane of the mandrel. Fig. 5 is a horizontal section of a portion thereof on the line 5 5, Fig. 4, looking downward. Fig. 6 is a vertical section of the lower portion of the

cutter and its accessories, the section being taken in the axial plane of the cutter. Fig. 7 is a side elevation of the lower portion of the cutter. Fig. 8 is an end view thereof. Fig. 9 is an elevation of one of the parts under slight modification.

A represents various parts of the frame of the machine, B is a hollow mandrel mounted to revolve therein, and C a pulley carried thereby, through which motion is transmitted to it. The mandrel has a tapering socket in which fits the tapering stem D' of the cutter D. As here shown, the cutter is of the type known as an "end-mill cutter," being provided on its end with teeth having radial cutting edges and being provided on its periphery with cutting-teeth, each tooth being separated from the next by a well-defined groove or channel. Ordinarily the rear side of each end tooth slopes from its front or cutting edge to the base of the front of the succeeding tooth; but for the purposes of our invention we prefer to shorten the rear face of each tooth and provide a well-defined groove or channel imme- 75 diately in front of the adjacent tooth. The cutter and its stem are hollow, and in it is disposed a tube E, which is closed at its lower end by an end piece e and is provided at one side and immediately adjacent to its lower end with an opening e' for the discharge of the lubricant. This opening is disposed directly opposite the channels in the end of the cutter, and the inner face of the end piece e is sloped downward toward the opening, terminating in 85 a sharp edge, in order to discharge the lubricant directly into the channels between the teeth, which are for the time being active, the channels between the inactive teeth being blanked or closed by the end piece e. 90 We prefer to use a tube E, constructed as described; but in its broadest aspect the invention is not limited thereto, but comprehends any device that will blank the channels between the inactive teeth of the cutter 95 and direct the entire volume of lubricant, or practically all of it, into the channels between the active teeth. We have therefore shown in Fig. 9 a rod or wire E', which is adapted to be substituted for the tube E, the lower end of the rod being provided with a foot or enlargement E'', one side of which is

adapted to blank the channels between the inactive teeth, its upper side being sloped downward to a thin edge, so as to direct the lubricant directly into the channels between 5 the active teeth. Without some means for blanking the channels between the inactive teeth the greater proportion of the lubricant would be discharged through them, as they would present the course of least resistance, 10 and this would be objectionable.

While we have specifically claimed in this application the particular means shown in Figs. 1 to 6, inclusive, for blanking the channels between the inactive teeth of the cutter, 15 we desire to have it understood that in its broadest aspect the invention is not limited thereto, but, on the contrary, includes any means for accomplishing this result, other means being shown in our application of even 20 date herewith, Serial No. 36,850, while still others will readily suggest themselves to those skilled in the art.

The machine shown in the drawings has a reciprocating bed-plate F, which may be actuated in customary or any desired manner. 25 It is desirable to have the cutter work during every reciprocation of the bed-plate, and with a cutter of the class shown in the drawings it becomes necessary to give the device for 30 blanking the channels between the inactive teeth a half-turn at the completion of each stroke of the bed-plate in order that the oil may be discharged, as above described, only into the channels between the active teeth. 35 To this end we secure to the tube a pinion G, with which meshes a toothed segment H, secured to the upper end of a rock-shaft I, the lower end of which carries an arm J, provided with studs K K', located in the path of stops 40 L L', carried by the bed-plate, one upon each side of the cutter. These studs K K' and the stops L L' are so disposed that when the bed-plate has just about completed its stroke in one direction one of the stops L L' will come 45 in contact with one of the studs K K' and move the arm J, the movement being transmitted through the rock-shaft I, segment H, and thence to the pinion G, by which the pinion is given a half-turn. In Fig. 5 the 50 parts are shown in the positions which they occupy when the cutter is about to complete its cut in the direction of the arrow on the work X. When the cut is complete, the stop L will come in contact with the stud K and 55 cause the above-described reversal in the position of the tube at about the time the movement of the bed-plate is reversed and before the stop L reaches the cutter.

In order to form a liquid-tight joint between 60 the mandrel and the tube, the mandrel is provided at its upper end with a stuffing-box consisting of a ring M, an elastic packing N, and a nut O, threaded to the mandrel, between which nut and the washer M the elastic 65 packing is clamped so as to form a tight joint around the tube. In order to form a liquid-tight joint between the tube and the fitting P,

with which is connected, the pipe P', leading from the pump or other source from which the lubricant is supplied, the fitting P is provided 70 with a stuffing-box consisting of a ring or washer M', an elastic packing N', and a nut O', which is screwed into the fitting, between which nut and the washer M' the elastic packing is clamped so as to form a tight joint 75 around the tube. The fitting P being stationary, the friction of the packing N' upon the tube will counteract the friction of the packing N upon the tube, and thereby tend to hold the tube against rotation due to the 80 frictional contact of the packing N with it; but in order to further insure the non-rotation of the tube it is surrounded and clamped by a split ring Q, carried by a rigid arm R, fixed to the frame of the machine. This clamp 85 and arm also serve to support the tube through the medium of the pinion G, which is non-rotatively secured to the tube and bears upon the clamp Q.

Having described our invention, what we 90 claim as new therein, and desire to secure by Letters Patent, is—

1. In a machine of the class described, the combination with a cutter having teeth and intervening channels, of means for discharging a lubricant into the channels between the teeth, and means for limiting the discharge to a limited number of the channels, substantially as set forth.

2. In a machine of the class described, the combination with a cutter having teeth and intervening channels, of means for discharging a lubricant into the channels between the active teeth, and means for preventing the discharge of the lubricant into the channels 105 between the inactive teeth, substantially as set forth.

3. In a machine of the class described, the combination with a cutter having teeth and intervening channels, said cutter having also 110 an internal passage, of means for causing a lubricant to flow through said passage and into the channels, and means for confining the flow of lubricant to a limited number of said channels, substantially as set forth. 115

4. In a machine of the class described, the combination with a cutter having on its periphery cutting-teeth and intervening channels and having in its end channels registering with the channels aforesaid, said cutter 120 having also an internal passage, of means for causing a lubricant to flow through said passage, thence into the channels in the end of the cutter and thence into the channels between the teeth, substantially as set forth. 125

5. In a machine of the class described, the combination with a cutter having on its periphery teeth and intervening channels and having in its end channels registering with the channels aforesaid, said cutter having 130 also an internal passage, of means for causing a lubricant to flow through said passage, thence through the channels in the end of the cutter and thence through the channels be-

tween the teeth, and means for confining the flow to the channels between the active teeth, substantially as set forth.

6. In a machine of the class described, the combination with a cutter having teeth and intervening channels, of a hollow stationary part having means for blanking a limited number of said channels, and means for causing a lubricant to flow through said stationary part and into the remaining channels, substantially as set forth.

7. In a machine of the class described, the combination with a cutter having on its periphery cutting-teeth and intervening channels and having on its end channels registering with the channels aforesaid, said cutter having also an internal passage, of means for causing a lubricant to flow through said passage and thence into the channels, and a stationary device within the cutter for confining the discharge to the channels between the active teeth, substantially as set forth.

8. In a machine of the class described, the combination with a cutter having teeth and intervening channels, said cutter having also an internal passage, of means for causing a lubricant to flow through said passage and escape therefrom into the channels, and a stationary device within the passage aforesaid for confining the discharge to a limited number of channels, substantially as set forth.

9. In a machine of the class described, the combination with a cutter having teeth and intervening channels and having an internal passage, of a stationary tube located in said passage, and means for causing a lubricant to flow through said tube and escape therefrom into the channels aforesaid, substantially as set forth.

10. In a machine of the class described, the combination with a cutter having teeth and intervening channels and having an internal passage, of a stationary tube located in said passage and having at its extremity an opening registering with a limited number of said channels, substantially as set forth.

11. In a machine of the class described, the combination with a cutter having teeth and intervening channels and having also an internal passage, of means for causing a lubricant to flow through said passage and thence into the channels, a stationary device located in the passage aforesaid and adapted to confine the lubricant to a limited number of said channels, and means for intermittently chang-

ing the position of said device, substantially as set forth.

12. In a machine of the class described, the combination with a cutter having teeth and intervening channels and having also an internal passage, of means for causing a lubricant to flow through said passage and thence into the channels, a stationary device located in the passage aforesaid and adapted to confine the lubricant to a limited number of said channels, and means for intermittently imparting a half-turn to said device, substantially as set forth.

13. In a machine of the class described, the combination with a cutter having teeth and intervening channels and having also an internal passage, of a stationary tube located in said passage, said tube having at its end an opening registering with a limited number of said channels, and means for intermittently imparting a part revolution to said tube for changing the position of the opening, substantially as set forth.

14. In a machine of the class described, the combination with a cutter having teeth and intervening channels, said cutter having also an internal passage, of means for causing a lubricant to flow through said passage and into the channels, a device located in the passage aforesaid for confining the lubricant to a limited number of said channels, a pinion carried by said device, a toothed sector engaging the pinion, a rock-shaft to which said sector is secured, an arm carried by said shaft, studs carried by the arm, and means carried by the reciprocating bed for engaging one or the other of said studs at about the completion of each stroke of the bed, whereby the shaft is alternately rocked in opposite directions and the position of the device aforesaid changed, substantially as set forth.

15. In a machine of the class described, the combination with a hollow cutter having on its end cutting-teeth and intervening channels and having also peripheral channels, of means for causing a lubricant to flow through said cutter, thence outward through the end channels and thence through the peripheral channels, substantially as set forth.
